UNITED STATES PATENT OFFICE

FRED E. KRAMER, OF CHARLOTTE, NORTH CAROLINA

HOSIERY HOLDER FOR FULL-FASHIONED FOOTING MACHINES

Application filed February 8, 1929. Serial No. 338,445.

This invention relates to improvements in hook bars for footing machines in the manufacture of full fashioned hosiery and relates more especially to improved means for holding the foot portion of the stocking in such a manner as not to tear or damage the same.

Another object of my invention is to provide improved means for holding the foot portion of a stocking in the manufacture of full-fashioned hosiery by providing clamping means for holding the silk portion of the foot portion of the stocking, and thus render the foot portion less liable to become damaged in the knitting operation.

Another object of my invention is to provide a holding mechanism for the foot portion of a stocking in the manufacture of full-fashioned hosiery, wherein the usual hooks are provided for holding the heel portions, but wherein I have provided clamping means for holding the silk portion of the stocking, said clamping means being capable of being opened very wide so as to allow the finger of the operator to be inserted between the jaws of the clamping means, thus rendering it very easy to place the stocking in the clamping means.

I am aware that heretofore means have been provided for clamping the silk portion of the foot of a stocking in the manufacture of full-fashioned hosiery, but in the means providing the gripping structure a very small opening is provided which renders it very difficult to secure the stocking in place, but in my improved mechanism the gripping member can be held opened with one hand while the other hand is free to press the stocking down between the grippers, and therefore a large portion of the stocking can be held in the grippers or any quantity of the stocking can be held in the said grippers.

The usual custom is to provide a hook bar having hooks such as are shown located at the end of my device, also in the middle of the hook bar for holding the silk portion of the stocking, but by the use of these hooks for holding the sheer portion of a stocking and especially in chiffon hosiery and other very thin types of hosiery, these hooks will tear the hosiery and otherwise damage

the same so as to render them unsalable or if salable will render them so damaged that they will have to be sold as "seconds."

Some of the objects of my invention having been stated, other objects will appear as the description proceeds when taken in connection with the accompanying drawings, in which—

Figure 1 is a plan view of a footing machine showing the portion with which my invention is adapted to be used;

Figure 2 is an enlarged cross-sectional view taken along the line 2—2 in Figure 1;

Figure 3 is a plan view of my improved hook bar and gripping means;

Figure 4 is a cross-sectional view taken along the line 4—4 in Figure 3;

Figure 5 is a cross-sectional view taken along the line 5—5 in Figure 3;

Figure 6 is a cross-sectional view taken along the line 6—6 in Figure 3;

Figure 7 is an end view of my device looking from along the line 7—7 of Figure 3;

Figure 8 is a cross-sectional view, taken along the line 8—8 in Figure 3;

Figure 9 is a view of the central portion of Figure 3, showing the clamping members in open position.

Referring more particularly to the drawings the numeral 10 indicates a portion of a footing machine of a well known make, and the numerals 11, 12, 13 and 14 indicate other parts of the footing machine which are not a part of my invention except in combination, and hence a description of the parts of the footing machine and their function is deemed unnecessary. This footing machine has the rotatable rod 15 on which the drum 16 is mounted, and the guiding rod 17 is also a part of this conventional machine. The machine is also provided with the conventional welt bar 18, and the sinker 19, all of which are conventional parts in a machine of this type.

The stocking body 20, is placed in the machine in the manner shown in Figure 1, and the same overlies the drum 16 and the guiding rod 17, this body of the stocking being arranged in the machine in the usual manner. The hook bar 21 has the conventional hooks

22 and 23 on the end thereof which are adapted to engage the heel portions 24 and 25 of the stocking, and this hook bar 21 has the slot 26 therein into which slot the tape member 27 is secured, and this tape member 27 runs backwardly and is secured in the drum 16. These hooks 22 and 23 hold the heel portion which is usually of cotton or a heavier grade of silk, and therefore not so liable to become torn, but I have provided improved means for holding the central portion of the stocking which is made of silk, which means will be presently described.

15 The tape 27 is secured in the slot 26 of the hook bar 21 by means of the rivet 28, or it can be secured by means of stitching or by any other suitable means.

20 My improved means for holding the central portion of the stocking, comprises a block 30 which is adapted to be secured to the hook bar 21 by means of the screw 31, this block 30 having the slots 32 and 33 cut in the outer ends thereof in which the levers 35 and 36 are adapted to be pivoted on the pins 37 and 38. This block has the downwardly projecting lug 39 which fits over the front edge 25 of the hook bar 21 to securely hold the block in position and to prevent the same from turning, when held by the screw 31. The forward portions of the levers 35 and 36 have enlarged circular portions as indicated at 40 and 41 in which the members 42 and 43, made of rubber or other resilient material, are adapted to be inserted, and to the other end 35 portions of the levers 35 and 36, the coiled tension springs 44 and 45, are secured, and the other ends of these springs 44 and 45 are secured to the hook bar by means of the screws 46 and 47, respectively.

40 It will be noted by observing Figure 9 to what extent the clamping members may be opened, it being evident from this illustration, that these may be opened very wide to allow the fingers or a portion of the hand of 45 the operator to be pressed downward between the members 42 and 43, carrying therewith the hose, and then when the fingers or hand is withdrawn, the hose will be clamped, thus 50 making it very easy to insert the hosiery in the clamping members, and it will also be evident that a large portion of the hose may be placed between the clamping members, if desired.

55 In the drawings and specification I have set forth a preferred embodiment of my invention, and although specific terms are employed they are used in a generic and descriptive sense only, and not for purposes of limitation, the scope of the invention being set forth in the appended claims.

I claim:

1. In a hook bar for footing machines, a body, a clamping structure mounted on said body, said clamping structure comprising two 65 pivotally mounted levers, tension means

adapted to normally hold one end of the levers against each other, said ends being provided with resilient members adapted to hold the hosiery in the footing machine.

2. In a hook bar for footing machines, a 70 clamping structure on said hook bar, said clamping structure comprising a block mounted on the hook bar, levers mounted in each end of the block, the forward ends of the said levers being provided with a resilient 75 substance, tension means adapted to hold the forward ends of the levers pressing against each other, said levers being adapted to be forced apart from each other at their forward ends to admit hosiery and being adapted to 80 normally press against each other at their forward ends to hold the hosiery in position.

3. Means for holding hosiery in a footing machine and the like, hook members adapted to hold the heel portion of the hosiery, two 85 pivotally mounted levers having resilient means in one 90 end thereof, and being adapted to hold the foot portion of the hosiery, tension means adapted to hold the resilient means against each other to securely hold the hosiery in 95 position.

4. In a hook bar for footing machines, a body portion, hooks on the end of the body portion, two pivotally mounted levers on the body portion, each of the levers having in 95 one end thereof resilient material, tension means connected with said levers and being adapted to normally press the ends having the resilient material against each other, said levers being adapted to be widely separated to facilitate the insertion of hosiery therein.

5. In a hook bar for footing machines and the like, two levers pivotally mounted on the hook bar, the forward end of the levers projecting forwardly of the hook bar, resilient 105 members mounted in said forward ends, and tension means associated with said levers and said hook bar adapted to normally press the forward ends of the levers against each other.

6. In a hook bar for footing machines, a 110 body, a clamping structure mounted on said body, said clamping structure comprising two pivotally mounted levers, separated tension means for each lever for normally holding one set of the ends of said levers against each other to thereby grip hosiery therebetween.

7. In a hook bar for footing machines and the like, two levers pivotally mounted on the hook bar, separated tension means for each lever for normally pressing the forward ends of the levers against each other to thereby grip hosiery therebetween.

In testimony whereof I affix my signature.

FRED E. KRAMER.
